UNITED STATES PATENT OFFICE.

PAUL SEILER, OF SAN FRANCISCO, CALIFORNIA.

TELEPHONE.

SPECIFICATION forming part of Letters Patent No 351,209, dated October 19, 1886.

Application filed February 20, 1885. Serial No. 156,583. (No model.)

To all whom it may concern:

Be it known that I, PAUL SEILER, of the city and county of San Francisco, State of California, have made and invented a new and 5 useful means of transmitting and receiving sounds in the form of an electric acoustic telephone receiver and transmitter; and I hereby declare that the following is a full, clear, and exact description of the same, reference being had to the accompanying drawings.

My invention relates to a novel means of receiving and transmitting sounds by telephone without battery-transmitters in connection with telephone-receivers.

The following description fully explains the character of my invention and the manner in which I proceed to construct, apply, use, and operate the same, the accompanying drawings 20 being referred to by figures and letters.

Figure 1 represents a vertical section, showing two diaphragms and the chain, wire, or cord connecting the same to transmit vibrations from one diaphragm to the other, as in 25 acoustic telephones. Fig. 2 represents two diaphragms and a steel magnet with a coil of wire, the same as are used in all telephone-receivers. Fig. 3 shows a bead-chain connecting the diaphragms. Fig. 4 shows wire used 30 for the same purpose.

The object of my invention is to increase the motion of the vibrating diaphragm of a telephone-receiver.

It is known that acoustic telephones are capable of giving, on short distances especially, 35 a very loud and distinct repetition of speech. This fact led me to think that the connecting medium—wire, cord, or chain—must exert considerable force when set in motion by 40 the diaphragm of the transmitter and produce considerable motion on the receiving-diaphragm. The ordinary Bell telephone-receiver, when made beyond a certain size, with a corresponding strong magnet, diminishes 45 very much when it is used as transmitter, the cause being that the diaphragm is held too rigid, being under the influence of the magnet, so that the voice must be raised much above the pitch of ordinary conversation to 50 be transmitted distinctly.

Referring to Fig. 1, A is a diaphragm of

any material ordinarily used in acoustic telephones; B, the wire or chain, and c a button to fasten the chain, which is a bead-chain and transmits with remarkable distinctness. This 55 chain is attached to an iron button, D, or armature of magnet, and I use an iron diaphragm, E, and place a magnet, F, with coils of insulated wire G, in front of diaphragm E. In using diaphragm A as transmitter the chain B 60 is set in motion and produces corresponding motion in diaphragm E in front of magnet F and coils G, which will transmit to the next station over line of wires H H. The operation is as follows: Diaphragm A vibrates chain 65 B, which sets in motion diaphragm E and button D in front of magnet F and coils G, and induces a current in coil G, which is transmitted over line H H. As a receiver this apparatus gives extraordinary results, and its operation 70 is as follows: The current of the distant telephone is received by the coil G, which causes diaphragm E to vibrate according to the power of the transmitting-telephone. Every vibration of diaphragm E is transmitted to dia- 75 phragm A, and this diaphragm is acted upon very acutely by the increased weight of chain B, the material in motion producing sounds loud enough to be heard without holding the ear to the receiver in the usual way. By this 80 arrangement a more powerful transmitter is substituted than can be produced by talking directly against the iron diaphragm under the immediate action of magnets, as is done in all Bell transmitters. This substitution dispenses 85 with battery-transmitters.

In Fig. 2 is the apparatus with suitable frames for diaphragms A and E, and the chain B, running through the tube I, which is composed of two pieces connected by another tube, 90 J. Both pieces of the main tube, as well as the connecting-tube, have right and left hand threads for the purpose of tightening the chain as required, in order to transmit well and to adjust the tube to the length of the chain. 95 The frame K, made of brass or other material, holds magnet F and coil G in position over diaphragm E. L is another magnet, which is bifurcated at its upper end to receive two coils, M, arranged as polarized bell coils, magnet M and F furnishing polarity for 100 the same by magnet L carrying the coils M.

Armature N of coils M is suspended by the bracket O, which is made of iron to furnish the required opposite polarity to armature, and is attached to magnet F, thus forming, 5 combined, a polarized bell and telephone receiver and transmitter and magnet and coils. The magnetic action in magnets F and L is connected through diaphragm E and on top of bracket O.

10 As I have explained, the object of my invention is to dispense with battery-transmitters in connection with telephone-receivers. I take two diaphragms—one of any kind of material and the other provided with an iron 15 armature or an iron diaphragm—and place in a suitable position the steel magnet and coils to act on the iron diaphragm. It will be seen that any vibration in the iron diaphragm is transmitted to the other diaphragm in the 20 same way as in any acoustic telephone; but as acoustic telephones transmit for short distances much stronger than electric telephones the sound will be heard very distinctly in the diaphragm not under the influence of magnetism, because the vibrations are stronger from 25 the action of the chain or wire. I find that on taking the similar magnet and coil of a Bell receiver out of the rubber case and placing them in the manner described I can hear 30 very distinctly two feet from the instrument, while in using the same magnet and coil in the case, as usual, I have to place the ear close to the telephone to hear the voice. Another advantage is obtained by using two dia- 35 phragms—namely, as it is impossible to speak against that side of the diaphragm in a Bell receiver which is against the magnet, I use

the other diaphragm in connection with a bead-chain, and speak into the top, as shown at P, Fig. 1. The pressure produced by the 40 voice is used to better advantage to wrench the upper diaphragm away from the magnet, by which stronger currents are induced in the coil of wire, and they consequently transmit stronger than by speaking against a dia- 45 phragm which has the tension produced by the magnet. In comparing it experimentally with an ordinary Bell receiver, it was shown that the voice is heard in a room, and is heard distinctly two feet from the instrument. These 50 tubes can be placed either vertical or horizontal; but the vertical position is preferred, because it takes less space and the chain transmits clearer and without metallic or rumbling noise. 55

Any number of mouth and ear pieces may be used, and in some cases an undulated wire may connect the diaphragms instead of a chain. This latter construction is more fully shown in Fig. 4. 60

Having thus fully described my invention, what I claim, and desire to secure by Letters Patent, is—

The combination, with the tube B, having mouth and ear pieces, of the diaphragms arranged at each end of said tube, and connected substantially as described, and the magnet F, provided with the coils G, and arranged above the diaphragm F, substantially as set forth. 65
